Daniels & Adrian, LLP(57) **CLAIM**

The ornamental design for an air conditioner, as shown and described.

DESCRIPTION

FIG. 1 is a top, front, and right side perspective view of an air conditioner, showing our new design.

FIG. 2 a top, front and right side perspective view thereof, showing the louvers in an alternate position.

FIG. 3 is a front elevational view thereof.

FIG. 4 is a right side elevational view thereof, the left side elevational view being a mirror image thereof.

FIG. 5 is a rear elevational view thereof.

FIG. 6 is a top plan view thereof, the bottom plan view being a mirror image thereof; and,

FIG. 7 is a cross-sectional view thereof, taken along line 7-7 of FIG. 3.

The broken lines illustrate environmental structure and form no part of the claimed design. The sectional view is provided to clarify the exact contour or configuration of the exterior surface of the air conditioner, and no attempt is made to illustrate all the features of the internal construction.
